DESIGN FOR A BOTTLE

Frank T. Kessler, Philadelphia, Pa., assignor to Continental Distilling Corporation, Philadelphia, Pa., a corporation of Delaware

Application December 19, 1933, Serial No. 50,111

Term of patent 14 years

To all whom it may concern:

Be it known that I, Frank T. Kessler, a citizen of the United States, residing at Philadelphia, in the county of Philadelphia and State of Pennsylvania, have invented a new, original, and ornamental Design for a Bottle, of which the following is a specification, reference being had to the accompanying drawing, forming part thereof.

The single figure of the drawing shows a perspective view of the bottle embodying my invention;—this perspective view being taken at a slight angle from above. The raised grill work continues generally throughout the circumference of the side of the bottle.

I claim:

The ornamental design for a bottle, as shown and described.

FRANK T. KESSLER.
